UNITED STATES PATENT OFFICE.

CROSBY FIELD, OF BROOKLYN, NEW YORK.

STEEL-WOOL MACHINE.

Application filed December 1, 1924. Serial No. 753,052.

My present invention relates to metal wool machines of the type in which several successive cutters operate simultaneously to cut metal wool from a wire which is reeled 5 back and forth lengthwise of the machine. Machines of this type commonly employ two lines or sets of the successive cutters, those of one set being oppositely directed from those of the other and the appropriately directed set being shifted laterally into engagement with the wire when the direction of reeling of the wire is reversed. Usually there is a separate cutter holder for each cutting blade, one cutter holder of each set 10 being mounted on a stand. Each stand is adjusted laterally on independent adjusting means, which is individually operated both for the above directed bodily shift of sets of cutters when the direction of the wire 15 is reversed and also for individual edgewise shift of any blade whenever the working portion of its cutting edge becomes too dull.

One object of my present invention is to 20 greatly increase the number of cutters that may be employed for simultaneous operation on a bed of given length. Another object is to greatly reduce the number of movements that are required to make the necessary adjustments of the cutters, particularly 25 when the direction of the wire is reversed.

One novel feature involves arranging both 30 of the sets of oppositely facing cutters in the same vertical plane of the wire and shifting the sets vertically instead of laterally, when the direction of the wire is reversed, lateral shift being used only for the individual shift which is necessary whenever the working portion of a blade becomes too dull. Preferably, the oppositely directed cutters 35 are not only in the same plane, but they are also in the same straight line and this makes possible a very desirable feature which consists in forming the oppositely directed cutters on opposite ends of a single blade. 40 Such single blade with two working ends, or the equivalent two-piece blade, is mounted in a single cutter holder which is adjustably rocked on a horizontal axis, both for universal shift of the sets of cutting edges when 45 the direction of the wire is reversed, and also for the purpose of varying the depth of cut of the individual blades during operation. Preferably, the cutter blades project equal 50 distances on opposite sides of the vertical plane of the axis of the cutter holder. The transverse shift of the blades is accom-

plished by an independent endwise adjustment of the cutter holder.

An important feature is providing all of the rocking cutter holders with parallel radial link members, all joined to a connecting bar so that they can be rocked in unison, independently of the minor individual adjustment of the knives for depth of cut which is by rocking the cutter holder with reference to these radial links.

Another feature of the invention is holding the knives in their adjusted position, mainly by the inertia of the parts and by the friction of the above described radius members, connecting bar and means for putting all of them under stress tending to increase such friction.

The depth of cutting of all of the tools may be simultaneously manually regulated 75 by a skilled operator, this result being preferably accomplished by using a universal shifting mechanism for the tools which may be frictionally held with the tools in any desired position of adjustment, the operator 80 skillfully shifting the common knife control member just far enough to bring most of the knives into proper cutting relation with the wire. There will usually be two or three knives of the set that the operator will have 85 to rectify for shallower or deeper cut, by fine adjusting mechanism, superposed on the universal shift. In other words, the means for finely adjusting each individual knife is entirely independent of the universal shift 90 which is operated only when the direction of movement of the wire is reversed.

For cutting the best quality of steel wool, the angle of the knife to the work should be about 16°. There is, however, a wide tolerance from a minimum of 11° to a maximum of about 26°. Consequently, the blades do not have to project equal distances from the pivotal axis of the blade holder although it is preferable that they do so. This tolerance 100 also permits the blades to be shortened a number of times by sharpening without materially affecting the quality of the product. A further feature of importance in this connection is the means for elevating the bed 105 of the machine to bring it closer to the blade holder and consequently reduce the cutting angle. Even after the bed has been raised to a maximum height, and the cutters reduced by shortening to a minimum length, 110 the same cutters may be used by shifting them in their holders each time that the di-

rection of movement of the wire is changed. This manual shifting adjustment of the blades, while not intended to be used in the ordinary course of operation is nevertheless 5 desirable because it practically eliminates the possibility of having to stop operation due to difficulty in obtaining new blades of the proper length.

The specific material which I prefer to 10 employ is steel wire or material of circular cross section such as is commonly supplied in bundle coils. The machine, however, is capable of operating on steel or other material in other forms, such for instance 15 as metallic wires, rods and bands of triangular, rectangular or other polygonal cross section and in fact may operate under some circumstances on plate or sheet material. In so far as the present invention 20 is concerned, the machine is capable of operating on materials other than the steel and of grooving for purposes other than the production of the specific product above mentioned.

25 The invention may be more fully understood from the following description in connection with the accompanying drawings, wherein—

Fig. 1 is a view in side elevation of a machine embodying the invention;

Fig. 2 is a fragmentary top plan view thereof;

Fig. 3 is a fragmentary view mainly in longitudinal section on the line 3—3 of 35 Fig. 2;

Fig. 4 is a transverse sectional view on the staggered line 4—4 of Fig. 3.

The machine includes a substantial frame work in the nature of a pair of two legged 40 stands 10, legs 10^a of the stands carrying endwise projecting brackets 11 in which the reels 12 are borne. Supported upon the stand 10 and set somewhat back from the front edge thereof are the ends of a pair of 45 beams 13 supporting a table 14 and extending longitudinally of the table, I provide a pair of parallel spaced tool holder frame bars 15 of substantial thickness. The forward frame bar 15 is arranged fairly close to 50 the front of the table and is abutted by the rear face of a longitudinally extending bed bar 16 having a curved upper edge which is highest at the center of the table. The bed blocks 17 are accommodated in a groove 18 55 in the bar 16 and are formed with shallow wire receiving grooves 19 in their upper surfaces. Blocks 17 are curved in conformity with the curvature of the bed bar, are vertically adjustable in the groove 18 upon 60 supporting screws 20, and may be locked against endwise movement in the groove by set screws 21. The reels 12 serve alternately as traction and supply reels, the wire 22 being dragged from one to the other over the 65 bed. Due to the curvature of the bed and

the fact that the reels are disposed below the level of the table, a downward stress will always be exerted on the wire stock to hold it firmly against the bed blocks. Any suitable number of straightening rolls 23 may 70 be employed at the ends of the table to prevent kinking of the stock. I have not illustrated the mechanism which is used for rotating the reels and effecting lateral feeding thereof for wire coiling purposes nor have 75 I shown means for reversing the feed and direction of rotation nor the releasable friction brakes whereby the supply reels offer proper resistance for maintaining a suitable tension on the wire to prevent overrunning, 80 since all such mechanism is entirely conventional in machines of this character and any means for rotating and reversing reels and causing them to draw the wire under tension 85 will serve the purpose of the present invention.

A series of transversely disposed tool holders 24 have parted rotary mounting in the frame bars 15. These tool holders are in the nature of shafts journaled in bushings 90 25 in the front frame bar and including enlarged rear ends 26 rotating in bearings 27 in the rear frame bar. The ends of the tool holders project beyond the front frame bed and over the bed and projecting ends are 95 formed with open ended tool holding slots 28 adapted to receive the grooving tools or knives 29. The bottom of the slot is in a plane parallel with the wire and serves as an 100 aligning guide with which a side edge of the blade contacts. The transverse axes of the tool holders are parallel and are disposed on an arc approximately parallel to the curvature of the upper surface of the bed bar 16 105 so that the distance between each of said axes and the surface of the bed is approximately the same. Consequently, for tools of similar length mounted in the holders the cutting angle relative to the work will be approximately the same.

A feature of the invention is the use of double acting cutting tools in the nature of plate-like members having grooved lower surfaces intersected by beveled end faces 115 providing a serrated grooving or cutting edge at each end of the tool. The tools are roughly centered in the holders with their two ends projecting from opposite sides of the slot 28 and held by clamping screws 32. The slot 28 is located below the axis of the holder so that the thrust of the wire on the cutter is nearly in the plane of the axis of the holder 24. It is obviously desirable 120 that the tools be fairly accurately centered in the slots so that the cutting angle of the tool relative to the wire will be the same regardless of which end of the tool is being used or which way the wire is running, but inasmuch as a tolerance of 15° is permissible, 125 this centering does not have to be ab- 130

solutely accurate. The tools are maintained in correct longitudinal alignment by backing them all the way into slots and abutting them against the straight bottoms thereof.

5 A feature of the invention is the provision of means for simultaneously tilting all of the tool holders about their respective axes in order to effect simultaneous shifting of the tools when the direction of movement of the 10 wire is reversed. Such mechanism includes a universal shift bar 35 extending longitudinally of the machine between the frame bars 15 and curved on the same arc as the bed. The projecting rear ends of bushings 25 provide a mounting for pairs of rectangular radius plates 36 spaced apart by collars 37 and pivotally connected at their upper ends with the universal shift bar 35 which passes between them. All of the pairs of radius plates 20 are of the same length and the relative positions of their two pivots maintain all of the pairs in absolute parallelism. A pivot pin 38 loosely entering aligned openings 39 and 40 in the shift bar and plates affords the necessary pivotal connection with the universal shift bar and the pivot pin is held in place by a keeper 41 secured to the face of the rear plate 36. Approximately three quarter cylindrical spacers 42 around the enlarged 30 ends 26 of the tool holder shafts between the rear block 15 and the rear radius plate 36 maintain the forward radius plates 36 pressed into close frictional engagement with the rear face of the front frame bar 15.

35 Brackets 43 secured to the tops of the pairs of radius plates 36 include overhanging rear edges 44 mounting pairs of adjusting screws 45 which work against opposite ends of hardened steel tilting levers 46 secured at their intermediate portion as by a screw 47, to the enlarged ends of tool holder shafts 24. Screws 46 are for the purpose of individual rotary adjustment of the tool holders independently of the simultaneous adjustment 40 obtained by the universal shift bar and it will be seen that adjustment in either direction may be effected by tightening on one screw and backing off on the other. The plates 36 have preferably a rather tight fit with the bushings 25 upon which they are pivotally mounted and due to the overhanging arrangement of the bracket 43 and the tendency of the adjusting screws 45 to tilt the plates 36 transversely and lift them upwardly, a further friction is induced between the front radius plate and the bar 15 and both radius plates and their bushing. The frictional resistance to movement of the 50 links may be further increased by keying the spacer members 37 to bushing 35 in any other convenient manner. This frictional resistance to the movement of the universal shift bar is quite important because it permits the bar to be shifted to any desired extent as by a lever 50 and automatically retained in its shifted position. When a skilled operator is reversing the knives after the direction of movement of the wire has been reversed, he moves lever 50 until approximately all of the knives have been brought into light contact 70 with wire and the frictional engagement of plates 36 with the frame bar 15 will retain the shift bar in such position until the lever is again operated. Operation of the universal shift will generally find one or more 75 of the knives slightly out of contact and they are manually adjusted for a shallower or deeper cut by use of the screws 45. These adjustments, however, are a negligible factor in the speed of operation as compared with 80 old machines wherein each tool was of necessity individually adjusted for depth of cutting every time the wire was reversed.

85 Due to the permissible tolerance in the cutting angle, the knives may be resharpened a number of times before such angle becomes excessive. Furthermore, all of the bed bars may be elevated to decrease the angle and, if desired, even very short knives may be used and shifted back and forth in their holders 89 upon each reversal of the wire. It will be noted that the upper surfaces of the universal shift bar is of wavy or undulating form, having high points at the pivots 38 and low points intermediate said pivots, in order 95 to provide clearance for the ends of the brackets 43 when the plates 36 are swung about their pivots.

90 The bar 35 may be shifted endwise to reverse the cutters, by applying endwise stress 100 to any portion of the bar or by pivoting any one of the radial brackets about its axis. Preferably, however, the lever is used and while such lever may have its arc of swing 105 the same as those of pivots 38, I prefer the arrangement shown in Fig. 3, where the lever has its fulcrum located above the bar 35 and pivoted to said bar as at 51 in such a way so that pivot 51 swings slightly downward at the time pivots 38 are swinging upward. The arcs are short and of slight curvature, however, so that the differential is not great and is permitted by ordinary radial play of pivots 50, 51, 38 and tool holder shaft 24, together with the slight elastic yield 110 of all of the parts. It is evident that there may be any desired phase relation between these two interfering arcs of movement, but I prefer to have the interference stress least at mid-stroke and greatest when the parts 115 are in the extreme positions at either end of the reversing movement. With the latter arrangement all of the pivots are put under opposing stresses, tending to take up all looseness and to afford maximum frictional locking effect tending to hold the cutter holders rigidly when they are in either of the working positions.

120 It will be understood that regardless of whether or not the shift lever has such 125

130

stress relation, the bar 35 and all the knife holders pivoted thereto are normally held in desired working position by inertia of the moving parts and also by their friction, particularly friction of the tool holding shaft 24 in the bearings by which it is supported and friction against the side faces of the radius plates.

A further feature of the invention is the provision of means for transversely shifting the tool holders to present new portions of the cutting edge of any tool to the work and insure the utilization of the entire cutting edge of the tool before resharpening becomes necessary. The means for performing this function is best seen in Fig. 4 and includes feed screws 60 working in threaded sockets 61 in the enlarged rear ends of the tool holders. The screws include shoulders 62 abutting plates 63 secured over the openings 27 in the rear frame bar. The unthreaded shanks 64 of the screws pass through the plates 36 and rotate in sleeves 65 retained by nuts 66. Each screw having bearings on the shoulder 62 and on the outer end of the sleeve 65. The squared extremities 67 of the screw carry crank handles 68 which are rotated to effect transverse feed of the tool holders. This transverse feed may become necessary at any time and the powerful propulsion obtained by the engagement of the feed screw with the holder is sufficient to overcome the slight friction of the rounded lower ends of the screws 45 and the hard steel tilting plates 46.

The steel wool cut by the machine falls to the floor in front of the machine or into a suitable receptacle provided for this purpose, so that no plucking or pulling of the wool by the operator is necessary.

I claim:

1. In a steel wool machine of the class described, a bed over which a length of material to be operated upon is alternately dragged in opposite directions, a plurality of rockable tool holders mounted adjacent the bed, a set of grooving tools in the holders and means for rocking the holders to reverse the position of the grooving tools, said means including a unitary tool shifting mechanism.

2. In a steel wool machine of the class described, a bed over which a length of material to be operated upon is alternately dragged in opposite directions, a plurality of rockable tool holders mounted adjacent the bed, a set of grooving tools in the holders and means for rocking the holders to reverse the position of the grooving tools, said means including a universal shift bar for simultaneously rocking all of the tool holders.

3. In a steel wool machine of the class described, a supporting bed, over which a length of metal stock is alternately dragged in opposite directions, a series of reversible

cutting tools arranged over the bed to operate on the stock, and means for simultaneously reversing the position of all of the tools.

4. In a machine of the class described, a supporting bed, means for dragging metal stock alternately in opposite directions across the bed, a plurality of tool holders having partial rotary movement, grooving tools in the holders, adapted to be moved into engagement with the work on the bed, upon partial rotary movement of the holders, a universal tool shifting means for simultaneously rocking all of the holders and adjusting mechanism superposed on the universal shifting means, for independently regulating the angle and depth of cutting of any of the tools.

5. In a machine of the class described, a bed over which a length of metal stock is adapted to be alternately dragged in opposite directions, a plurality of tool holders having partial rotary movement arranged above the bed, grooving tools secured in the holders with their cutting ends disposed on opposite sides of the rotary axes of the holders, a universal shift bar for simultaneously rocking all of the holders to reverse the position of the tools when direction of the movement of the work is reversed.

6. In a machine of the class described, a bed over which a length of metal stock is adapted to be alternately dragged in opposite directions, a plurality of tool holders having partial rotary movement arranged above the bed, grooving tools secured in the holders with their cutting ends disposed on opposite sides of the rotary axes of the holders, a universal shift bar for simultaneously rocking all of the holders to reverse the position of the tools when direction of the movement of the work is reversed, a plurality of pivoted radius plates to which the shift bar is pivotally connected and means operatively connecting the radius plates and the tool holders.

7. In a machine of the class described, a bed over which a length of metal stock is adapted to be alternately dragged in opposite directions, a plurality of tool holders having partial rotary movement arranged above the bed, grooving tools secured in the holders with their cutting ends disposed on opposite sides of the rotary axes of the holders, a universal shift bar for simultaneously rocking all of the holders to reverse the position of the tools when direction of the movement of the work is reversed, a plurality of pivoted radius plates to which the shift bar is pivotally connected and means operatively connecting the radius plates and the tool holders, including tilting plates fixed to the tool holders, brackets secured to the radius plates and thrust screws carried by the brackets and engaging the tilting plates.

8. In a machine of the class described, a bed over which a length of metal stock is adapted to be alternately dragged in opposite directions, a plurality of tool holders having partial rotary movement arranged above the bed, grooving tools secured in the holders with their cutting ends disposed on opposite sides of the rotary axes of the holders, a universal shift bar for simultaneously rocking all of the holders to reverse the position of the tools when direction of the movement of the work is reversed, a plurality of pivoted radius plates to which the shift bar is pivotally connected and means operatively connecting the radius plates and the tool holders, including tilting plates fixed to the tool holders, brackets secured to the radius plates and thrust screws carried by the brackets and engaging the tilting plates, said thrust screws constituting means for rocking the tool holders to regulate their angle and depth of cutting independently of the universal shift bar.
9. In a machine of the class described, a bed over which a length of metal stock is adapted to be alternately dragged in opposite directions, a series of reversible grooving tools arranged above the bed, rocking tool holders supporting the tools, a universal shift bar for simultaneously rocking all of the holders to reverse the positions of the tools and means frictionally opposing the movement of the shift bar whereby said tools may be retained in any angular position relative to the work.
10. A device of the class described in claim 9 wherein an individual angular adjustment of the tools is superposed upon the universal adjustment effected by the shift bar.
11. A machine of the class described, including a supporting bed over which a length of metallic stock is adapted to be alternately dragged in opposite directions, a tool holder frame including an elongated frame plate mounted adjacent the bed, rotary tool holders journaled in the frame plate, grooving tools mounted in the holders, a universal shift bar for simultaneously rocking all of the holders, radius plates supporting the shift bar, and operatively connected to the holders and means for causing the friction between the radius plates and the tool holder frame to oppose movement of the shift bar and permit all of the holders to be retained in any position of adjustment.
12. In a machine of the class described, a bed over which a length of metal stock is adapted to be alternately dragged in opposite directions, a plurality of grooving tools arranged above the bed, rockable tool holders supporting the tools mechanism for rocking the tool holders to reverse the grooving tools and means for feeding the holders transversely of the bed to present a new portion of the cutting edge of a tool to the stock.
13. In a machine of the class described, a bed, over which a length of metallic stock is adapted to be alternately dragged in opposite directions, a plurality of rotatable tool holders arranged adjacent the bed, cutting tools supported in the holders, tilting plates fixed to the holders and thrust screws engageable with opposite ends of the tilting plates to effect partial rotary movement of the holders.
14. In a machine of the class described, a bed over which a length of metal stock is adapted to be alternately dragged in opposite directions, a plurality of rotatably adjustable tool holders arranged adjacent the bed, cutting tools in the holders, a universal shift bar for simultaneously operating the holders, a plurality of pivoted radius plates pivotally connected to the shift bar, said radius plates being of equal length and parallel to each other, and means operatively connecting the shift bar and the tool holders.
15. A device of the class described in claim 14, wherein means is provided for frictionally opposing the pivotal movement of the radius plates to permit the shift bar to be retained in any position of adjustment.
16. In a machine of the class described, a bed, over which a length of metallic stock is adapted to be alternately dragged in opposite directions, a plurality of rockable tool holders, shafts journaled transversely of the bed, and constituting tool holders, tilting plates fixed to the shafts, thrust screws engaging opposite ends of the tilting plates, swinging brackets carrying the thrust screws, and a universal shift bar for simultaneously swinging all of the brackets to effect partial rotation of the shafts.
17. A machine of the class described, including a bed over which a length of metal stock is alternately dragged in opposite directions, a series of reversible grooving tools arranged above the bed, a tool holder frame extending longitudinally of the bed, transversely disposed tool holders rotatably mounted in the frame, tilting plates on the tool holders, thrust screws engaging the tilting plates and operable to effect rotational adjustment of the tool holders and means for shifting the tool holders axially to present new portions of the cutting edge of the tool to the work.
18. A machine of the class described, including a bed over which a length of metal stock is alternately dragged in opposite directions, said bed including a plurality of vertically adjustable bed blocks having grooves therein for receiving and guiding the stock, rotatable tool holders having slotted tool holding ends projecting over the

- bed and cutting tools having their intermediate portions disposed in the slots and their ends extending on opposite sides thereof. 55
19. A machine of the class described, including a bed, over which a length of metal stock is alternately dragged in opposite directions, said bed including a plurality of vertically adjustable bed blocks having grooves therein for receiving and guiding the stock, rotatable tool holders having slotted tool holding ends projecting over the bed and cutting tools having their intermediate portions disposed in the slots and their ends extending on opposite sides thereof, 60 tilting plates on the tool holders and thrust screws engaging the tilting plates to regulate the angle of cutting. 65
20. A machine of the class described, including a bed, over which a length of metal stock is alternately dragged in opposite directions, said bed including a plurality of vertically adjustable bed blocks having grooves therein for receiving and guiding the stock, rotatable tool holders having slotted tool holding ends projecting over the bed and cutting tools having their intermediate portions disposed in the slots and their ends extending on opposite sides thereof, tilting plates on the tool holders and 70 thrust screws engaging the tilting plates to regulate the angle of cutting of the tools, and screw feed mechanism for axially shifting the tool holders transversely of the bed to present new portions of a cutting edge 75 of a tool to the work. 80
21. A steel wool machine of the class described, including a bed over which wire stock is adapted to be alternately dragged in opposite directions, in combination with a linked pivotal system including a plurality of rockably mounted tool holders, grooving knives in said tool holders, a universal shift bar operatively connected to all of the tool holders, parallel pivoted radius members of approximately equal radii pivotally connected to and supporting the shift bar, and means for shifting the shift bar. 90
22. A steel wool machine of the class described, including a bed over which wire stock is adapted to be alternately dragged in opposite directions, in combination with a linked pivotal system including a plurality of rockably mounted tool holders, grooving knives in said tool holders, a universal shift bar operatively connected to all of the tool holders, parallel pivoted radius members of approximately equal radii pivotally connected to and supporting the shift bar, and means for shifting the shift bar. 95
23. A steel wool machine of the class described, including a curved bed over which wire to be worked upon is alternately dragged in opposite directions, in combination with a plurality of rotatable tool holders having approximately parallel transverse axes disposed in an arc approximately parallel to the curvature of the bed, oppositely projecting grooving knives mounted in the tool holders and having both ends in the longitudinal vertical plane of the bed, means for simultaneously rotating all of the tool holders to reverse the direction of operation of the knives when the direction of movement of the wire is reversed, said means including a shift bar, a plurality of approximately parallel radius members each pivoted upon an axis concentric with the axis of one of the tool holders, a universal shift bar operatively connected to the tool holders and pivotally connected to each of the radius members, and an operating lever for the shift bar, said operating lever and the end of the shift bar to which it is connected swinging on interfering arcs. 100
24. A machine of the class described in claim 23 and wherein the interference stress is increasingly great toward the ends of the strokes of the shift bar. 105
25. A machine of the class described in claim 23 and wherein the interference stress is greatest at the time that the weight of the swinging parts acts most forcefully on the tools to force them into engagement with the work. 110
26. A machine of the class described in claim 23 and wherein the weight of the swinging parts acts to force the tools against the work and said interference stress acts counter to said weight. 115

Signed at New York, in the county of Kings, and State of New York, this 26th day of November, A. D. 1924. 120

CROSBY FIELD.
